UNITED STATES PATENT OFFICE.

CHARLES H. HARKINS, OF ST. LOUIS, MISSOURI, ASSIGNOR TO THE WESTERN
BRASS MANUFACTURING COMPANY, OF SAME PLACE.

DESIGN FOR A BRACKET.

SPECIFICATION forming part of Design No. 18,814, dated December 18, 1888.

Application filed September 29, 1888. Serial No. 286,793. Term of patent 7 years.

To all whom it may concern:

Be it known that I, CHARLES H. HARKINS, a citizen of the United States, residing at St. Louis, in the State of Missouri, have invented 5 and produced a new and original Design for a Bracket for Wash-Bowls and the Like, of which the following is a specification, reference being had to the accompanying drawing, forming part thereof.

10 The drawing is a perspective view showing my design.

1 represents a horizontal arm or plate, and 2 is a vertical arm or plate.

15 3 represents a ring contiguous to and within the angle of the arms, having a clear opening, and having protuberances 4 at its periphery.

5 represents an arm extending upward, out-

ward, and laterally from the arm 2 to one of the protuberances 4, and having a down-turned end, 6; and 7 represents an arm extending downward, outward, and vertically from the arm 1 to the other protuberance 4, and having an outturned end, 8.

9 represents a protuberance extending from the ring to the arm 1, and 10 represents a protuberance extending from the ring to the arm 2.

I claim as my invention—

The design for a bracket, substantially as herein shown and described.

CHARLES H. HARKINS.

In presence of—

SAML. KNIGHT,
EDW. S. KNIGHT.
